UNITED STATES PATENT OFFICE.

BASIL J. YANCHENKO, OF NEW YORK, N. Y., ASSIGNOR TO THE PROSPERITY COMPANY, INC., OF SYRACUSE, NEW YORK, A CORPORATION OF NEW YORK.

POWER PRESS.

Application filed August 14, 1925. Serial No. 50,173.

This invention appertains to ironing machines and more particularly to power presses for ironing laundered goods and in some cases for garment seam and edge pressing 5 work where considerable pressure is required on the garment.

An object of this invention is to produce a power press suitable for laundries and the like or for clothes pressing which machine is 10 provided with wide opening jaws affording extended visibility of the work and which is closed by motor means and which is safe to operate.

A further purpose is to produce a power 15 press of simple construction wherein I am enabled to use a continuously running motor capable of imparting intermittent pressure operations and to this end a freely swinging cam member travels over a continuously running drive roller for a predetermined period of time to maintain compression between the jaws on the work, and when the cam reaches the end of its travel and the compression period is completed the pressing jaws are then 25 automatically opened, and I provide a novel structure and mode of operation for securing these results.

Among other things, an important object 30 of the invention is to employ a continuously running motor as aforesaid without resorting to the use of a clutch which is oftentimes employed in power presses to acquire the necessary start and stop motion. I acquire the stop and start motion by an improved 35 roller and cam combination and in doing so I take advantage of economy in power in employing a continuously running motor and eliminate the disadvantage ordinarily attending clutches and similar mechanisms. Thus 40 by using a continuously running motor without a clutch, I greatly simplify power presses and ironers.

The accompanying drawing illustrates an 45 example of the invention serving to illustrate its principle and mode of operation and it is appreciated that changes may be made without departing from the principles involved.

Figure 1 illustrates a side view of the press 50 in open position with the power cam in inoperative position at the time it is about ready to start the press closing operation by power. In this view the press closed position of the cam is shown in dotted lines.

Figure 2 illustrates a top view of the double safety hand control by which both hands of the operator are compelled to be used to close the press.

Figure 3 is a fragmentary rear view of the 60 press while closed under pressure.

Figure 4 is a cross sectional view of a rotating power closing wheel which takes hold of the press closing mechanism to close the press jaws and which then release the mechanism to other means by which pressure is 65 exerted for a prolonged duration.

Figure 5 is a fragmentary side view of the press in closed position.

Referring further to the drawing for a more detailed description of the invention 70 there is shown a press frame 10 supporting a lower ironing or pressing buck 11 and which is adapted to receive the work which is pressed or ironed by the head 12. The pressing or jaw members 11 and 12 are suitably 75 heated as by steam or otherwise. A press lever 14 is pivoted at 15 on the frame 10.

A pendulous cam 18 is pivoted at 19 on the rear end of the press lever 14 and a counter balance weight 20 may be attached to the 80 upper end of the swing link 18. This weight 20 serves not only to aid in balancing the press lever 14 and head jaw 12 or slightly overbalancing the head 12 to lift it but serves as well to slightly over-balance the freely 85 swinging cam member so that its lower cam-way 22 is caused to normally stand forwardly toward the front of the press.

A roller end 24 is the extremity of a power 90 shaft 24 journaled in a gear reduction housing 26 and the working face 22 of the cam 18 travels across the roller shaft end 24 in executing the pressing operation. A motor 28 drives through gear reductions 23 and through a shaft 29 into the gear housing 26 95 and a worm pinion 30 is fixed to the shaft 29 on the inside of the housing which meshes with a worm wheel 31 fixed on the power shaft 24 thereby slowly driving the power shaft.

The power driven shaft end 24 turns at relatively slow speed by reason of the gear reduction either contained within the housing 26 or elsewhere as shown at 23. Inasmuch as the roller 24 travels at substantially low peripheral speed, it follows that the cam face 27 dwells or prolongs its engagement with the roller 24 for a predetermined time there-

by maintaining the period of compression on the work between the press jaws so long as it requires for the cam 22 to traverse the shaft roller end 24.

- 5 The cam frame 18 carries its cam face 22 in an offset relation so that the upper portion of the frame 18 stands to one side of the cam 22 and away from the roller 24 with the result that the cam may traverse or swing laterally across or past the roller 24 from its lower rearmost position to its forward lowermost position. The offset roller-way passage 36 through the cam frame 18 shown in Figure 3 permits this movement from said rearwardly 10 low swinging position to the forwardly low position and the weight 20 acts upon the cam frame 18 to urge it forwardly and hold it there because, as already explained, the said weight 20 over-balances the cam 22 causing it 15 to swing across the roller 24 without interference therewith by reason of the ample clearance space 36 afforded between the roller and the cam frame 18 by reason of the cam-way 22 being offset from the frame 18.
- 20 25 As hereinbefore stated, this power press embodies power closing means by which the head or upper press jaw is brought down upon the work without requiring physical exertion on the operator's part, and the power closing mechanism functions with considerable celerity so that little time is lost by the closing operation. The press having completed the pressure operation, opens by gravity. A description of these features will now 30 be given.

40 A rotating disk, wheel or crank 40 is fixed on the shaft 24, and the fact that the shaft 24 projects from the disk 40 a short distance affords the power shaft roller end 24 which 45 revolves under the cam 22 as already described. The disk 40 is adapted to close the press jaw 12 down on the work, but without pressure, by taking hold of the cam frame 18 and quickly lifting it upwardly to swing the press lever 14 on its fulcrum 15.

50 The disk 40 carries a pin 41 normally urged outwardly by a spring 41' and projecting from the face thereof which is adapted to engage and pick up a hook 42 formed integrally 55 on the cam frame 18. Observing Figure 1 which shows the press open with the cam frame 18 down and observing that the rotating disk and pin 41 move in counter-clockwise direction, it is evident that the pin 41 would 60 engage the hook 42 at the time the pin 41 reaches its lowermost position provided that the hook 42 is at that moment lifted by the operator into alignment with said rotating pin 41. However, Figure 1 shows the cam frame hook 42 outside of the path of travel of the pin 41, and therefore the motor 28 continues to drive the disk 40, the pin 41, and the pressure roller 24 without in any way interfering with the normally open position of

the press, and so the operator is free to adjust the work in between the jaws.

Means are provided by which the operator initiates the power closing operation by manually lifting the cam frame 18 just enough to permit the pin 41 to pick up the hook 42 to close the press, and such means embody safety apparatus by which the operator may not accidentally injure his hands between the press jaws. A description of the operator controlled mechanism will now be given.

75 A control lever 44 is pivoted in the press frame at 45 and this lever is made with a lifting head 46 reaching rearwardly and disposed under the edge of the cam 22. This lever 44 is also provided with a stop hook 47 against which the upper corner of the cam frame rests to bring the cam frame 18 into normal non-operative position and to hold it there against the urge of the counter-balance weight 20. A link 48 is pivotally connected 80 at 49 to the lever 44 and is pivotally connected at 50 to an arm 60 which is fixed on a shaft 61 journaled in the frame 10. This shaft 61 carries loosely mounted thereon, referring to Figure 2, hubs 62 with integral handles 63 90 and 64 projecting therefrom. Each handle 63 and 64 is loosely mounted on the shaft 61 and rotates thereon without moving the shaft. The arm 60 is integrally formed with a hub 65 which is also freely journaled to 95 rotate on the shaft 61 without effecting movement of shaft 61. In other words, the shaft 61 merely supports the three hubs 62 and 65 journaled thereon. A lever 66 is pivoted at 67 on the hub 65, so this lever 66 is directly 100 connected with the arm 60. Each outer end of the lever is slotted as at 68 and each slot embraces a pin 69 anchored in the two handle hubs 62.

105 The foregoing paragraph describes the safety handle structure shown in Figure 2 and by way of describing its operation, it is noted that any attempt to move the handle 64 alone, merely results in pivoting the lever 66 at its fulcrum 67 without moving the arm 60, and so 110 it follows that the link 48 is not moved and the control lever 44 is not moved when the operator attempts to do so with one hand. However, if the operator will grasp the handles 63 and 64 with his two hands, respectively, it follows 115 that the swing lever 66 enforces movement of the hub 60 and therefore swings arm 60 rearwardly which transmits motion to the control lever 44 thereby disengaging stop hook 47 from cam frame 18 and simultaneously 120 lifting the head 46 against the lower edge of the cam 22. This operation of both handles 63 and 64 causes the frame 18 to be lifted up a short distance thereby bringing the lift hook 42 into alignment with the traveling pin 41.

125 As the pin 41 approaches lowermost position, it engages hook 42 and quickly carries the cam frame 18 upwardly thereby bringing

the head 12 down upon the work but without exerting any pressure thereon. When the hook 42 and pin 41 have reached uppermost position, the result is that the cam 22 is placed upon the roller 24 and the cam frame 22 is caused to travel rearwardly under clockwise rotation of the power roller 24. The power roller 24 being comparatively small in diameter, has a low peripheral speed and the cam 22 therefore dwells for a certain pressing period as it slowly moves to the rear of the press. The front edge of the cam drops off of the roller at the end of the pressing operation, and the combined weight of the counter-weight 20 with the weight of the cam frame 18, causes the head 12 to be lifted. At the same time, the offset position of the cam frame 18 permits this cam to again swing forwardly to non-operative press opened position as shown in Figure 1 and thereby come to rest against the stop hook 47 awaiting the next pressing operation.

The spring 41' permits the pin 40 to slide back into the crank wheel 40 each time it moves around into sliding engagement with the rear inclined surface of the hook 42 and thus pass the hook for it is noted that the pin 41 will make several revolutions about the shaft roller 24 before the cam 22 is fully traversed.

The pendulous cam frame 18 embodies a combination of novel press features which enable the press to be rapidly closed under the force of the continuously running motor 28, and subsequently there follows a slow high compression duration by reason of the fact that the small diameter roller 24 rolls under the cam 22. The operative exchange is automatically effected as between the rapidly moving lifting hook 41 and the slowly rotating power pressure roller 24.

The press is safe to operate because it cannot be closed unless the operator uses both hands which compels him to remove his hands from the vicinity of the closing jaws. A marked advantage exists in the continuously running motor, and a particular feature and advantage of this invention resides in the fact that I employ a continuously operating motor to close the press under effort of the motor and thereafter produce compression by the motor without stopping and starting it.

What I claim is:

1. A press comprising in combination, operating wide opening press jaws, a cam connected with one of the press jaws to produce jaw compression, means cooperating with the cam urging it to an inoperative position, a motor, a roller continuously driven by the motor and adapted to engage the cam, power closing means operated by the motor to close the press jaws, means to permit the cam to pass by the roller without being engaged by said roller, operator actuated means to cause the cam to be brought into position to be engaged by

the power closing means and subsequently engaged by the roller aforesaid to produce compression between the jaws.

2. A press comprising in combination, operating wide opening press jaws, a cam connected with one of the press jaws to produce jaw compression, a weight means urging the cam to an inoperative position, a motor, a roller continuously driven by the motor and adapted to engage the cam, power closing means operated by the motor, means to permit the cam to pass by the roller without engaging said roller, and a manually actuated control handle to lift the cam into engagement with the power closing means. 70

3. A press comprising in combination, operating wide opening press jaws, a press lever carrying one press jaw and adapted to move this jaw relatively to the other, a cam pivotally suspended from the press lever, a motor driven roller continuously revolving and adapted to cooperate with the cam to drive it in one direction to produce jaw compression, a passage formed along the cam enabling it to travel past the roller in the other direction to seek an inoperative position of rest, press closing means driven by the motor to lift the cam and close the press, and an operator actuated device to render effective the operation of the press closing means. 85

4. A press comprising in combination, operating wide opening press jaws, a press lever carrying one press jaw and adapted to operate said jaw relatively to the other jaw, a cam swingably attached at one end thereof to the press lever, means cooperating with the cam urging it normally forwardly and upwardly, a continuously revolving power closing wheel including means adapted to take hold of the cam and lift it to close the press, a continuously rotating motor driven roller adapted to cooperate with the swinging cam to produce jaw compression, and means forming part of the cam structure enabling it to pass by the roller and return to normal inoperative position. 100

5. A press comprising in combination, operating wide opening press jaws, a press lever carrying one press jaw and adapted to open and close the press, a cam swingably pivoted at one end thereof to the press lever and adapted to impose pressure on the lever after the press closes, weight means cooperating with the cam acting through the pivot urging it normally upwardly and forwardly to an inoperative position, a motor driven roller continuously revolving and adapted to engage the swinging cam and drive it in one direction to produce pressure as aforesaid, means forming part of the cam structure enabling it to pass by the roller with clearance without being engaged thereby while the cam is moving to its inoperative position, a power closing means by which the press is closed, and means operable by 115 120 125 130

the operator to move the cam into line with the press closing device.

6. A press comprising in combination, a frame, cooperating wide opening work jaws between which the work is pressed, a press lever fulcrumed in the frame and having one end thereof attached to a jaw to open and close the press by a swinging up and down lever motion, a pendulum cam pivotally connected with the other end of the press lever, a motor driven roller which may engage and traverse the cam when the lever swings to close the press, a motor driven press closing device, manually operable means to urge the cam to a position to be engaged by the press closing device, and means acting on the cam and press lever causing the press to open after the cam traverses the roller and causing the cam to return to a normally inoperative position ready for the next pressing operation.

7. A press comprising in combination, a frame, a press lever pivotally carried in the frame, jaws opened and closed by the lever, an elongated member having a cam surface at one end and being pivotally connected at the other end to the press lever, a motor, a roller driven by the motor and slowly revolving in engagement with the cam surface for a predetermined time to produce jaw compression through the lever, a weight carried by the lever and by the elongated member which causes the cam end of said member to move away from the roller and simultaneously open the press at the end of the pre-

determined pressing period, and power means operated by the motor to close the press.

8. A press comprising in combination, cooperating pressing jaws, a press lever adapted to open wide and close the jaws, a pendulum member having a cam surface at one end and being pivotally connected at the other end to the press lever, a motor driven roller slowly revolving in engagement with the cam surface to produce jaw compression through the lever, a weight carried by the lever and by the pendulum member which causes said member to move away from the roller and open the press at the end of the pressing period, an offset passage made on the elongated member which permits it to swing past the roller to find its inoperative position, power closing means to close the press jaws, and a manually operable means to render effective the power closing means.

9. A press comprising in combination, cooperating press jaws, a press lever to open and close the jaws, a pendulum cam pivotally connected to the press lever, motor means continuously operating, mechanism operated by the motor means to close the press without compression, a roller to run under the cam at the end of the closing operation to produce compression, and a manually operable device to lift the cam into a position to be engaged by the press closing means.

In testimony whereof I affix my signature.

BASIL J. YANCHENKO.
